COMBINATION SHOE TREE AND SHOESHINE
BRACKET

Verne Clair, Rye, N. Y.

Application May 4, 1946, Serial No. 667,240

3 Claims. (Cl. 12—128.6)

1

This invention is a combination shoe tree and shoe-shine bracket, the shoe tree being adapted for use in the conventional fashion to keep the shoe, with which it is used, free from wrinkles and in its proper shape, and the bracket permitting the shoe tree to be attached to a support to provide the shoe-shine bracket. The combination is an improvement over the art in that it provides a sufficiently convenient and sturdy arrangement to persuade people to actually shine their own shoes.

A specific example of the invention is illustrated by the accompanying drawings in which

Figure 1 is a top view of the invention in use as a shoe-shine bracket;

Fig. 2 is a side view of Fig. 1;

Fig. 3 is a perspective of a detail;

Fig. 4 is a top view of the shoe tree;

Fig. 5 is a side view of Fig. 4;

Fig. 6 is a longitudinal section taken from the line 6—6 in Fig. 4; and

Fig. 7 is a cross-section taken from the line 7—7 in Fig. 5.

More specifically, these drawings illustrate the invention as including a shoe tree having a front main portion 1 and a heel portion 2 with these portions interconnected by an assembly comprising a flat bar 3 that is hinged to the front portion 1 and a socket bar 4, rigidly fixed to the heel portion 2, in which the bar 3 slides. Relative sliding of the bar 3 and the socket bar 4 is adjustably restrained by a screw 5 screwed into the bar 3 and extending up through a slot 8 in the socket bar 4, this screw having a flange 9 that frictionally engages the top of the socket bar 4 when the screw is screwed into the bar 3. This provides a convenient, foolproof adjustment for changing the size of the shoe tree. In use, the forward portion 1 is thrust into the shoe and the heel portion 2 then swings downwardly so that the shoe tree snugly fits into the shoe. For convenience in removing the shoe tree, the heel portion 2 is provided with a knob 29 extending above the top of the shoe so that it may be grasped easily for lifting the heel portion out of the shoe first, whereupon removal of the shoe tree is easy.

The front portion 1 is designed to fill the forward portion of the shoe in the usual manner, but it differs from the usual shoe tree design in that it has a full instep portion 10 and in that the central portion of this instep portion has a longitudinally-extending socket 11 aligned with the center of the bottom of the shoe tree along a line transversely aligned with the ball portion of the front portion 1. This socket may be made

in various ways, but, since the shoe tree front portion 1 is made entirely of wood in this specific example, it is here provided by a groove, in the bottom of the instep portion 10, which is closed by a metal plate 12, screwed to this bottom by screws 12a, which extends upwardly in alignment with the socket 11 in the form of a tongue 13. Figs. 5 and 6 show these screws 12a going through the plate 12 into the instep portion 10 on either side of the groove in the bottom of this instep portion, these screws being free from the groove as shown in Fig. 6. By providing the shoe tree front portion 1 with the full instep portion 10, the entrance to this socket 11 is positioned so as to be easily accessible when the shoe tree is inserted in a shoe. This is particularly so in the case of a low shoe, as is illustrated particularly well by Fig. 2, but it is reasonably accessible even in the case of a high shoe. Other materials may, of course, be substituted for wood.

The shoe-shine bracket is in the form of a straight, flat metal bar 14, the socket 12 being shaped for fitting by the lower end of this bar 14 and this lower end being provided with a screw 15 that is threaded through it for engagement with the tongue 13, the latter preferably having a depression for receiving the screw end. By screwing down on the screw, which is readily accessible from above the bar and beyond the end of the instep portion 10, the shoe tree becomes firmly fixed to the lower end of the bar 14, unscrewing of the screw effecting its release when desired. Both this screw 15 and the screw 5 are preferably provided with knurled heads 16 and 17, respectively, for facilitating their screwing and unscrewing. Other quick-releasable fastenings may be substituted for these screw arrangements.

The upper end of the straight, flat bar 14 is bent downwardly to provide a depending end 18 adapted to be received by a fixture 19 that can be screwed permanently to a wall or other support. This fixture 19 has a groove 20 in its back for receiving the end 18, the latter being merely dropped into this groove when it is desired to attach the bar 14 to the support. Other fastening means may be used but this general type is preferred. The angularity of the end 18 respecting the bar 14 should be such as to hold the shoe substantially horizontal, and, if other fastening means are used, they should be designed to do the same thing.

By arranging the flat bar 14 transversely flatly, it is transversely wider than it is thick, but it should be thick enough to prevent undue motion

of the shoe tree when it is stressed by the polishing operations. However, the bar should not be so thick as to rigidly resist all of the vertical shoe-polishing stresses, the idea being that it should have sufficient elasticity to permit slight vertical movement of the shoe tree and thus absorb some of the vertical shoe-shining stresses, whereby these stresses are transmitted to the fixture 19 in a form free from sudden shocks. This permits a relatively small attachment, of the general type illustrated, to function effectively to position the shoe, through the medium of the parts mentioned, during the shoe-shining operations. If the bar 14 were made sufficiently massive to be rigid, or if it were designed so as to vertically depend from a rigid arm, a much more massive attachment would have to be used to fasten the bracket to the wall or other support. This is because such rigid arrangements transmit all of the sudden shocks directly to the bracket, whereas in the case of the present invention the angularity of the bar 14 and its very slight but appreciably elastic vertical flexibility serves to relieve the attachment from such sudden shocks.

Furthermore, the angularity of the socket 11 is such that when the bar 14 extends from the instep portion 10 to a fixture designed to fasten the upper end of the bar to a vertical wall or other support, with the shoe tree in a horizontal plane, the bar naturally assumes an angle best suited to remove torque from the fixture while still spacing the shoe tree far enough from a vertical wall to permit polishing of its back portion. Preferably, the angularity is such that the angle between the bottom of the bar 14 and a vertical line depending from the fixture 19 is about 90°. This angularity has been found best for accomplishing the purposes mentioned.

As shown by Figs. 1 and 2, the extended instep portion 10 works together with the above-discussed angularity to make it very convenient for the user to thrust the bar 14 into the socket 11 and lock it in position by the use of the screw 15. Then, by dropping the depending end 18 into the fixture 19, permanently fixed to a wall, he is ready to start shining his shoe. As he shines the shoe, the vertical force applied to the shoe, usually as shock in the case of a vigorous shoe shining, is elastically absorbed by the bar 14 so as to prevent its transmission to the fixture 18 excepting as comparatively smoothly-applied force. Since the bar 14 is transversely wider than it is thick, it has comparatively no flexibility transversely, this rigidly positioning the shoe transversely. Since transverse force is transmitted to the fixture 19 in a direction that the latter is best able to withstand, the direct transmission of shock, due to the width of the bar, is not of great importance; that is to say, the fixture 19 is more apt to pull out of the wall than it is to turn and, in any event, most of the shoe-shining shock is in a vertical plane. The angularity of the bar 14, respecting the fixture 19, further contributes to relieving the fixture from undue stress. It is to be understood that the reason it is desired to reduce the stress on the fixture 19 is because this fixture must be mounted permanently to the wall and should, therefore, be

small in size, so as to be inconspicuous, and mounted by comparatively small screws or the like so as to permit its easy attachment to the wall by the user.

5 I claim:

1. A shoe tree having a substantially full instep portion with its central portion having a longitudinally-extending socket substantially aligned with the center of the bottom of said shoe tree along a line transversely aligned with the ball portion thereof, a straight bar having a lower end fitting slidably in said socket and an upper end provided with releasable means for mounting it to a support with said shoe tree substantially horizontal, and releasable means for retaining said bar's lower end in said socket.

10 2. A shoe tree having a substantially full instep portion with its central portion having a longitudinally-extending socket substantially aligned with the center of the bottom of said shoe tree along a line transversely aligned with the ball portion thereof, a straight bar having a lower end fitting slidably in said socket and an upper end provided with releasable means for

15 mounting it to a support with said shoe tree substantially horizontal, and releasable means for retaining said bar's lower end in said socket, said bar being transversely wider than it is thick to resist transverse flexing while permitting at least limited vertical flexing when vertical force is applied to said shoe tree.

20 3. A shoe tree having a substantially full instep portion with its central portion having a longitudinally-extending socket substantially aligned with the center of the bottom of said shoe tree along a line transversely aligned with the ball portion thereof, a straight bar having a lower end fitting slidably in said socket and an upper end provided with releasable means for

25 mounting it to a support with said shoe tree substantially horizontal, and releasable means for retaining said bar's lower end in said socket, said bar being transversely wider than it is thick to resist transverse flexing while permitting at least limited vertical flexing when vertical force is applied to said shoe tree.

30 35 4. A shoe tree having a substantially full instep portion with its central portion having a longitudinally-extending socket substantially aligned with the center of the bottom of said shoe tree along a line transversely aligned with the ball portion thereof, a straight bar having a lower end fitting slidably in said socket and an upper end provided with releasable means for

35 40 45 mounting it to a support with said shoe tree substantially horizontal, and releasable means for retaining said bar's lower end in said socket, the last-named means including a releasing element accessible from above said bar and beyond the end of said instep portion.
